Primary Examiner — Susan E Krakower(74) *Attorney, Agent, or Firm* — Gordon G. Waggett, P.C.(57) **CLAIM**

The ornamental design for the weighted exercise pants, as shown and described.

DESCRIPTION

FIG. 1 is a front perspective view of a weighted exercise pants showing our new design.

FIG. 2 is a front view thereof.

FIG. 3 is a back view thereof.

FIG. 4 is a left side view thereof.

FIG. 5 is a right side view thereof; and,

FIG. 6 is a second front view thereof, showing how the unclaimed weights are inserted.

The broken lines illustrate environmental structure and form no part of the claimed design.

It is understood that the broken lines within the claimed design indicate stitch lines which form part of the claimed design.
